CLAIM

The ornamental design for a grow light, as shown and described.

DESCRIPTION

FIG. 1 is a front perspective view of a grow light of the present invention;

FIG. 2 is a front elevation view of the grow light of FIG. 1; FIG. 3 is a back elevation view of the grow light of FIG. 1; FIG. 4 is a right side view of the grow light of FIG. 1; FIG. 5 is a left side view of the grow light of FIG. 1; FIG. 6 is a top plan view of the grow light of FIG. 1; and, FIG. 7 is a bottom plan view of the grow light of FIG. 1. The broken lines shown in the drawings represent portions of the grow light and form no part of the claimed design.

1 Claim, 5 Drawing Sheets
